(57) **CLAIM**

The ornamental design for a helmet pad structure, as shown and described.

DESCRIPTION

FIG. 1 is a perspective view of a helmet pad structure having an array of individual pads.

FIG. 2 is a top view of the helmet pad structure of FIG. 1.

FIG. 3 is a bottom view of the helmet pad structure of FIG. 1.

FIG. 4 is a front end view of the helmet pad structure of FIG. 1.

FIG. 5 is a rear end view of the helmet pad structure of FIG. 1.

FIG. 6 is a right side view of the helmet pad structure of FIG. 1.

FIG. 7 is a left side view of the helmet pad structure of FIG. 1.

FIG. 8 is a front perspective view of the helmet pad structure of FIG. 1 shown in a folded conformation as when it is to be fitted within a helmet.

FIG. 9 is a top view of the helmet pad structure of FIG. 8.

FIG. 10 is a bottom view of the helmet pad structure of FIG. 8.

FIG. 11 is a left side view of the helmet pad structure of FIG. 8.

FIG. 12 is a right side view of the helmet pad structure of FIG. 8; and,

FIG. 13 is a rear perspective view of the helmet pad structure of FIG. 8.
